Inventor:

Samuel E. Jarvis
by his Atty. *W. S. Sprague*

UNITED STATES PATENT OFFICE.

SAMUEL E. JARVIS, OF LANSING, MICHIGAN.

BALANCED STEAM-VALVE.

SPECIFICATION forming part of Letters Patent No. 267,791, dated November 21, 1882.

Application filed August 31, 1882. (No model.)

To all whom it may concern:

Be it known that I, SAMUEL E. JARVIS, of Lansing, in the county of Ingham and State of Michigan, have invented new and useful Improvements in Balanced Steam-Valves; and I do hereby declare that the following is a full, clear, and exact description thereof, reference being had to the accompanying drawings, which form a part of this specification.

10 The nature of this invention relates to certain new and useful improvements in the construction of balanced steam-valves for steam-engines; and

15 The object of the invention is, first, to provide the valve with additional induction-ports, so as to more rapidly allow the steam to enter the cylinder; and, secondly, to secure a perfect balance of the valve in all its different positions.

20 Figure 1 shows the valve-chest opening the induction-ports. Fig. 2 shows it in a position when such ports are closed. Fig. 3 is a cross-section on the line *x x* in Fig. 1.

25 In the accompanying drawings, which form a part of this specification, A represents the cylinder, and B the steam-chest, and C the slide-valve. The cylinder is what is known as a "three-ported" one, *a b* being the induction-ports, and *c* the exhaust-port, and all arranged in the usual way. The steam side of the slide-valve forms an exact counterpart of its exhaust side, both being parallel, and provided with the induction-ports *d d' d'' d'''*, which are arranged and connected together as shown.

30 *e* is a central passage, which connects the exhaust-port *f* of the valve with a recess, *g*, of the same area, on the opposite side of the valve.

35 *h h* are small brass tubes, open at both ends, and arranged between the ports *d* and *f* and *d'''* and *f*, and form steam-passages from the lower to the upper side of the valve.

40 *G* is a face-plate, provided with recesses *j k*, which correspond in position and superficial area exactly and respectively with the induction and exduction openings *a b c* in the valve-seat *K* of the cylinder. This face-plate is also provided with the flanges *I I*, which form guides for the slide-valve in its

travel, and prevent the face-plate from pressing upon the valve and binding it, said face-plate acting as a guide for the valve by embracing it upon three of its sides. The face-plate *G* is prevented from lateral displacement in any proper manner, without, however, interfering with its vertical play, which is allowed to a very slight extent, as there is a little open space, *l*, left between the top of this plate and the valve-chest cover. This is to allow the valve to rise from its seat and pass water from the cylinder back to the chest.

45 It will be seen, in the operation of the valve, that as soon as an induction-port in the cylinder is uncovered steam will pass into the same directly from the valve-chest, as in the usual manner, and also indirectly through three induction-ports in the valve, as in Fig. 1, through the ports *d d' d'' d'''*, which pass the steam through the remaining port *d* into the induction-port *a* of the cylinder. This arrangement, being otherwise desirable, admits also of a more limited 50 travel of the valve. The second object of my invention is likewise gained through this arrangement of the valve induction-ports *d d' d'' d'''*, as these ports, in addition to the port *e* and relief-ports *h*, will at all times form an equilibrium in pressure on both sides of the valve. The necessity of the brass tubes *h h* is clearly indicated in Fig. 2, as in this position of the valve they form the only effective relief-ports for balancing the same. It is clear that the 55 same construction may be applied to a so-called "double valve."

60 What I claim as my invention, and desire to secure by Letters Patent, is—

65 The valve *C*, having induction-ports *d d' d'' d'''*, balancing-passages *h*, and exhaust-port *e*, combined with the seat having ports *a b c*, and with the plate *G*, having corresponding spaces, *j k*, and flanges *I*, the said plate *G* embracing the valve upon three sides, and being arranged to form space *l*, as set forth.

70 SAMUEL E. JARVIS.
